UNITED STATES PATENT OFFICE.

FRANK C. GRIFFITH, OF BOSTON, MASSACHUSETTS.

DESIGN FOR A CONDIMENTS-HOLDER FOR PLATES.

SPECIFICATION forming part of Design No. 21,539, dated May 17, 1892.

Application filed November 4, 1890. Serial No. 370,354. Term of patent 3½ years.

To all whom it may concern:

Be it known that I, FRANK C. GRIFFITH, a citizen of the United States, residing at Boston, in the county of Suffolk and State of Massachusetts, have invented and produced a new and original Design for a Condiment-Holder, of which the following is a specification, reference being had to the accompanying drawings, forming part thereof, which are deemed necessary and sufficient to fully illustrate my design.

Figure 1 is a plan or top view of a condiment-holder embodying my invention. Fig. 2 is a cross-section taken on line xx of Fig. 1. The leading features of my design consist in a body substantially of an obtuse-pointed heart shape, the point being extended and doubled under the main portion and almost parallel therewith, the tip of the extension being slightly curved away from the main

body. The top of the main portion is provided with two elliptical depressions at the upper or larger part, and with a small substantially semi-elliptical depression between the two depressions and the obtuse point. ²⁵

In the drawings, A indicates the body; B, the two elliptical depressions; C, the small depression, and D the portion of the point that is extended and doubled, as shown.

What I claim is—

The design for a condiment-holder for a plate, as herein shown and described.

In testimony whereof I have signed my name to this specification, in the presence of two subscribing witnesses, on this 13th day of October, A. D. 1890.

FRANK C. GRIFFITH.

Witnesses:

GEORGE A. O. ERNST,
WM. W. STOREY.
